(57) **CLAIM**

The ornamental design for a grille for vehicle or replica thereof, as shown and described.

DESCRIPTION

FIG. 1 is a front elevation view of a grille for vehicle or replica thereof in accordance with the present design;

FIG. 2 is a front elevation detail view thereof;

FIG. 3 is a left side elevation view of the detail shown in FIG. 2, the right side elevation view thereof being a mirror image of the left side elevation view;

FIG. 4 is a top, front, and left side perspective view of the detail shown in FIG. 2; and,

FIG. 5 is a front and left side perspective view of the detail shown in FIG. 2.

The broken lines in the drawings illustrate portions of the grille for vehicle or replica thereof that form no part of the claimed design.

1 Claim, 5 Drawing Sheets
